UNITED STATES PATENT OFFICE

PEARL INGRAM, OF LOS ANGELES, CALIFORNIA

DESIGN FOR A BAG HANDLE

Application filed December 10, 1930. Serial No. 37,936. Term of patent 3½ years.

To all whom it may concern:

Be it known that I, PEARL INGRAM, a citizen of the United States, residing at Los Angeles, in the county of Los Angeles and State of California, have invented a new, original and ornamental Design for a Bag Handle, of which the following is a specification, reference being had to the accompanying drawings, forming part thereof.

I claim:

The ornamental design for a bag handle as shown.

PEARL INGRAM.
